UNITED STATES PATENT OFFICE.

HERMANN JOOS, OF BERLIN, GERMANY, ASSIGNOR TO GENERAL ELECTRIC COMPANY,
A CORPORATION OF NEW YORK.

TAPPED TURBINE.

1,093,934.

Specification of Letters Patent. Patented Apr. 21, 1914.

Application filed November 8, 1912. Serial No. 780,217.

To all whom it may concern:

Be it known that I, HERMANN Joos, a citizen of the Swiss Republic, residing at Berlin, Germany, have invented certain new and useful Improvements in Tapped Turbines, of which the following is a specification.

This invention relates to elastic fluid turbines in which provision is made for drawing off a portion of the steam after it has passed one or more high pressure stages, and utilizing it for heating or other industrial purposes. It is customary to regulate the admission of steam to the turbine by a speed-responsive device in accordance with the variations in load.

My invention has for its object the additional regulation of the admission of such steam in accordance with the variations in the consumption of steam for heating.

The essential features of construction and mode of operation are hereinafter set forth, and particularly pointed out in the appended claims.

In the accompanying drawing, Figure 1 is a somewhat diagrammatic representation of a tapped turbine embodying my invention, the important parts being shown in section, and Fig. 2 is a section of the pilot valve and sleeve for the throttle valve motor.

Through the casing 1 of the turbine runs the shaft 2, carrying the high pressure bucket wheel 3 and also low pressure wheels 4, of which one is shown. Steam is admitted to the high pressure stage through one or more nozzles 5, and to the low pressure stage through nozzles 6. The high pressure steam is conveyed to the machine by a main 7 and its flow is controlled by a suitable regulator, such as a balanced throttle valve 8, the amount of whose opening is regulated by a speed governor 9 through a lever 10 which operates the pilot valve 11 of a hydraulic motor whose piston 12 is connected to the stem of the throttle valve. The admission of steam from the high pressure stage chamber 13 to the low pressure nozzles is controlled by a balanced overflow valve 14, whose stem is connected to the piston of a hydraulic motor 15 having a pilot valve 16 actuated by a movable abutment, preferably a weighted piston 17.

The conduit 18 for leading off the heating steam opens from the chamber 13, and a pipe 19 runs from said conduit to the mov-

able abutment 17, so that the opening and closing of the overflow valve 14 is governed by the pressure prevailing in the heating conduit. In the conduit 18 is inserted a section 20 having a constriction 21, so that said section constitutes a Venturi tube. A pipe 22 runs from this constriction, or throat, to the underside of a weighted piston 23, whose upper side is subjected to the stage pressure in the chamber 13 by means of a pipe 24. The piston 23 is connected by a lever 25 with a sleeve 26 inclosing the pilot valve 11 and containing ports 27. In the mid-position of said valve, these ports are closed, so that no fluid pressure can enter the wider ports 28 which lead to the spaces above and below the piston 12.

The operation is as follows: If, for example, there is an increase in the amount of steam consumed in the industrial apparatus, then first the pressure in the conduit 18 falls. The corresponding reduction in pressure in the pipe 19 permits the piston 17 to move the pilot valve 16 and thus cause the motor 15 to close the overflow valve 14. This produces a rise in pressure in the stage chamber 13 and increases the flow of steam through the conduit 18. In accordance with the established law of pressures in a Venturi tube, this increase in steam flow causes a variation from the former ratio between the high pressure pipe 22 and the low pressure pipe 24. This pressure difference moves the piston 23 downward, which pulls the sleeve 26 upward and thus admits fluid pressure below the piston 12 to open the high pressure regulator 8. It thus appears that with an increasing demand for industrial steam the overflow valve 14 is closed and at the same time the high pressure regulator is opened, and this takes place without substantially affecting the speed governor 9. Suppose, however, that the load on the turbine is increased. This causes the speed governor to open the high pressure valve 8, so that the pressure in the chamber 13 increases and also in the conduit 18, assuming no increase in the demand for industrial steam. The pressure regulator 17 thereupon opens the overflow valve 14 so that the extra steam flows to the low pressure stage to assist in carrying the load, while the pressure in the heating pipe is restored to normal.

In accordance with the provisions of the 110

- 2
- patent statutes, I have described the principle of operation of my invention, together with the apparatus which I now consider to represent the best embodiment thereof; but
- 5 I desire to have it understood that the apparatus shown is only illustrative, and that the invention can be carried out by other means.
- What I claim as new, and desire to secure by Letters Patent of the United States, is:—
- 10 1. The combination with a turbine, of a regulator therefor, a speed governor for controlling the regulator, a conduit for drawing off motive fluid for industrial purposes, and means responsive to a change in the
- 15 rate of flow of the fluid passing through the conduit for modifying the action of the regulator.
- 20 2. The combination with a turbine, of a regulator therefor, a speed governor for controlling the regulator, a conduit for drawing off motive fluid for industrial purposes, and means responsive to a change in the rate of flow of the fluid passing through the conduit for causing the regulator to admit
- 25 more fluid to the turbine as the rate of flow through the conduit increases and causing the regulator to admit less fluid to the turbine as the rate of flow decreases, said means acting independently of the governor.
- 30 3. The combination with a turbine having a high pressure regulator controlled by a speed governor, of a conduit for drawing off steam for industrial purposes, means responsive to changes in the rate of flow in said
- 35 conduit for exerting an additional governing effect upon said regulator, and independent means responsive to pressure changes of the steam drawn off through said conduit for additionally controlling the passage of steam through the turbine.
- 40 4. The combination with a turbine having a high pressure regulator, of a motor for actuating the same, a speed governor connected to the pilot valve of said motor, a
- 45 conduit for drawing off steam for industrial purposes, and means responsive to changes in the rate of flow in said conduit for exerting an additional control of said motor.
- 50 5. The combination with a turbine having a high pressure throttle valve, of a motor for actuating said valve, a pilot valve for said motor, a regulating sleeve inclosing said pilot valve, a speed governor connected to said pilot valve, a conduit for drawing off steam for industrial purposes, and means responsive to the rate of flow in said conduit for shifting said regulating sleeve.
- 55 6. The combination with a turbine having a high pressure throttle valve and an overflow valve to a low pressure stage, of a conduit for drawing off steam for industrial purposes, and separate devices responsive to the pressure and to the rate of flow in said conduit respectively for closing the overflow valve and opening the high pressure throttle valve when the demand for industrial steam increases.
- 60 7. The combination with a turbine having a high pressure throttle valve, of a conduit for drawing off steam for industrial purposes, a Venturi section in said conduit, and means responsive to pressure differences in said Venturi section for regulating the throttle valve.
- 70 8. The combination with a turbine having a high pressure throttle valve, of a conduit for drawing off steam for industrial purposes, a Venturi section in said conduit, a weighted piston controlling said throttle valve, and pipes running to opposite sides of said piston from regions of pressure difference in said Venturi section.

In witness whereof, I have hereunto set my hand this 4th day of October, 1912.

HERMANN JOOS.
